UNITED STATES PATENT OFFICE.

ROBERT C. ALLEN, OF SWARTHMORE, PENNSYLVANIA, ASSIGNOR TO WESTINGHOUSE ELECTRIC & MANUFACTURING COMPANY, A CORPORATION OF PENNSYLVANIA.

TURBINE-COOLING MEANS.

Application filed December 23, 1925. Serial No. 77,419.

My invention relates to elastic fluid turbines, more particularly to means for maintaining an even distribution of heat in the rotors thereof when idle, and has for its object the provision of a method and apparatus whereby said even distribution of heat is readily effected.

Apparatus embodying features of my invention is illustrated in the accompanying drawing wherein Figure 1 is a view in elevation of a turbine with my invention applied thereto and having certain parts broken away to better show the apparatus together with a diagrammatic showing of an electrical circuit employed therewith, and Figure 2 is an enlarged diagrammatic view of a detail of the invention.

Whenever an elastic fluid turbine, particularly one of the multi-stage type, has been in operation and is shut down for a comparatively short period of time, difficulties have been encountered in again putting it in operation due to rubbing of the parts and unbalance of the rotor. This has been found to be caused by an unequal distribution of heat throughout the mass of the turbine rotor. When the turbine is stopped the rotor and blading, or parts thereof, are at a temperature approximating that of the motive fluid which may be as high as 700° F. While standing idle, the conduction of heat through the surrounding casing is the cause of convection currents in the air or mixture of air and steam in the casing. These, in turn, create zones of higher temperature at the top of the rotor than at the bottom thus causing the top of the rotor to remain temporarily at a higher temperature than at the bottom. As the lower part of the rotor cools, it contracts and becomes shorter than the upper part resulting in a warping of the rotor so that there is an appreciable upward bow or bend therein. If the turbine is again started with the rotor thus temporarily bent it will be found to be decidedly out of balance so that rubbing of the parts is liable to occur and the turbine be seriously damaged.

The degree to which a rotor becomes unbalanced is determined by its mass, its length, the temperature thereof at the time it is stopped, and the interval of time it has been stopped. In accordance with my invention I determine the maximum upward

warping of the rotor within which the turbine may be safely started, the time in which the maximum allowable upward warping occurs and within which the turbine may be again safely started, and turn the rotor through a sufficiently wide arc, substantially 180°, so that another, cooler part thereof is placed upwards and the hotter part downwards. The placing of the hot part of the rotor downwards and of the cool part upwards cools the lower, hotter part and heats the cooler part and thus effects a straightening of the rotor. Should the lower part again become cooler than the upper part and the rotor again become warped upwardly, it may be turned a second or a third time according to the circumstances.

In carrying out the invention, I provide gear means associated with the turbine shaft and adapted to turn the rotor when idle, and I provide a motor for actuating the gear means. A chronometric device is provided for controlling the motor circuit so that the motor is started at the proper interval of time after the turbine is stopped, determined by the rate of warping of the rotor. After the turbine shaft is turned through an arc of approximately 180°, the motor circuit is opened and the motor stopped. Should the turbine remain stopped through another predetermined interval of time, the motor is again started and the rotor again turned through 180°. By this means the rotor never warps sufficiently to prevent the turbine's being started promptly.

Referring now to the drawing for a better understanding of my invention, I show a turbine 10 having a rotor 11 and a shaft 12. At 13 is shown gear means arranged on the shaft, for example, in the turbine coupling housing, shown at 14. Extending transversely of the shaft 12 is a shaft 16 having provided thereon a worm 17 which is adapted to mesh with the gear teeth 13. The shaft 16 is slidable longitudinally to the left of its position shown in Fig. 1, to permit disengagement of worm 17 and gear teeth 13. When the turbine is in operation its normal direction of rotation is in the direction of the arrow at 18, so that the worm 17 is automatically thrown out of engagement with the gear 13 when the turbine is being operated by motive fluid. On one end of the shaft 16 is provided manual

means, such as a hand wheel 19, for engaging the worm 17 with the gear 13 when the turbine is idle and it is desired to turn the rotor thereof. This is done by rotating the shaft 16 which screws the worm 17 into engagement with gear teeth 13. A squared end 21 is also provided on the shaft 16 for the attachment of a suitable tool for manually turning the turbine rotor 11 when desired.

As before pointed out, when the turbine is first stopped and its rotor is heated, it cools faster at the bottom than at the top and effects an upward warping or bending of the rotor. Within certain limits, the upward bending of the rotor may be unobjectionable, but beyond said limits, depending on the time the rotor has been stopped, difficulties are encountered in again starting the turbine. In order to determine the rate of upward bending of the rotor 11, I show a measuring device 22 adapted to indicate the clearance between the casing and the rotor. By taking readings when the rotor has normal clearance and at intervals while cooling, the rate of upward distortion due to unequal distribution of heat in the mass thereof may be ascertained. For example, if it is found that at the termination of a period of two hours after shutting down, the rotor has been bent upwardly as far as allowable limits, I then turn the same by means of the shaft 16 and worm 17 through an arc of 180° so that the hotter part is placed downwardly and the cooler part upwardly. With the rotor turned in this manner, the heat thereof, is carried upwardly by conduction and convection, the hotter part becomes cooler and it straightens. If the continued cooling in the new position again causes an upward warping of the rotor to unsafe limits it may again be turned through 180° .

In order that the above described action may be carried out automatically, I show a motor 24 connected to the shaft 16 by a sliding coupling 26 so that the worm 17 may be readily disengaged from the gear 13. Driven from the opposite end of the motor shaft is a worm 27 engaging with a gear 28 with the same gear ratio as the worm 17 and the gear 13 so that the gear 28 makes a complete revolution in the same time as the gear 13 and the worm 17 when in mesh.

The motor 24 is controlled by an electrical circuit embodying two branches 29 and 30 which have included therein two brushes 31 and 32 which bear on concentric rings 33 and 34 on the face of the gear 28. Approximately half of each of the rings 33 and 34 comprises conducting material and the other half insulating material. A third brush 36 bears on both of the rings 33 and 34 and connects to one of the motor leads. A source of electrical energy is indicated at

37 and is connected to the other motor lead through a controlling switch 38 of the oscillating, double snap, double contact type.

It will be apparent from the drawing that with the switch 38 in the position shown and the brush 32 bearing on the conducting material of the ring 33, the motor circuit is complete and the motor will operate until the gears 28 and 13 have each completed a half revolution or until the brush 32 is bearing against the insulating material of the ring 33. If the switch 38 be now turned to connect with the branch 30 the motor circuit will then be completed through brush 31, ring 34 and brush 36 and the motor again operates until the gears 28 and 13 have each turned a half revolution.

The switch 38 is controlled by a chronometric device 39 which has an indicating element 40 included in an electrical circuit 41 having a solenoid winding 42 incorporated therein. The moving element 43 of the solenoid is biased upwardly by a spring 44 and has depending therefrom a flexible member 46. When the circuit 41 is energized, the flexible element 46 moves downwardly, striking the switch 38, whereupon it is turned to the right or to the left, as the case may be, completing the motor circuit through the branches 29 or 30. In order that the circuit 41 may be energized at periods of time determined by the rate of warping of the rotor 11 I show branches 45-45 leading to equal divisions of time on the chronometric device 39 so that, when the moving element 40 touches at the points indicated, the circuit 41 is completed.

The operation of the apparatus is as follows: The rate of upward bending or warping of the rotor 11 is first determined by means of the measuring device 22 and the maximum allowable warping within which the turbine may be safely started is determined. The leads 45 of the electrical circuit 41 are next distributed around the dial of the chronometric device so as to cause the electrical circuit 40 to be completed at regular intervals within which the rotor is to be turned. When the turbine is stopped, the shaft 16 is pushed toward the gear 13 by means of the hand wheel 19 and is screwed in until the worm 17 is in mesh with the gear 13. The chronometric device 39 is then started and the moving element 40 is turned to contact with one of the leads 45-45 whereupon the motor starts and is turned until stopped by reason of one of the brushes 31 or 32 moving off of the conducting material of the rings 33 or 34.

The rotor now stands idle until the moving element 40 again contacts with one of the leads 45 whereupon the motor is started and the rotor is turned through an arc of 180° as previously described. The rotor again stands idle through the period of time

determined by its rate of warping when the moving element 40 again energizes the electrical circuit 41, completes the motor circuit and the rotor is again turned through 5 an arc of 180°. In the manner described the proper distribution of heat in the rotor 11 is maintained so that the turbine may be started at any time after being stopped without danger of rubbing of the parts or 10 excessive vibration.

From the foregoing it will be apparent that I have devised a method and apparatus for maintaining an even distribution of heat in a turbine rotor when idle.

15 What I claim is:—

1. The combination with an idle turbine having a heated rotor, of means other than motive fluid for turning the rotor, and means determined by the rate of cooling of the mass 20 of the rotor for periodically stopping and starting the turning means.

2. The combination with an elastic fluid turbine having a rotor, of means adapted to operatively engage with the rotor and turn 25 it during idle periods, and means including a chronometric device adapted to start and stop said turning means at predetermined periods of time, said periods of time being in accordance with the distribution of heat 30 in the rotor mass.

3. The combination with an elastic fluid turbine having a rotor with a shaft, of an electric motor, gearing means between the electric motor and the shaft whereby the motor is adapted to turn the rotor during idle 35 periods, an electric circuit for controlling the motor, a chronometric device adapted to close the motor circuit at predetermined intervals of time, and means responsive to a 40 predetermined arc of revolution of the rotor for opening the motor circuit.

4. The combination with an elastic fluid turbine having a rotor with a shaft, of gear means arranged on the shaft, a worm adapted 45 to engage with the gear means for rotating the shaft when the turbine is idle and adapted to disengage when the turbine is being operated, a motor for driving the worm, and means responsive to time cooperating 50 with a predetermined arc of revolution of the shaft for starting and stopping the rotor.

5. The combination with an elastic fluid turbine having a rotor with a shaft, of gear 55 means arranged on the shaft, a worm adapted to engage with the gear means for rotating the shaft when the turbine is idle and adapted to disengage when the turbine is being operated, a motor for driving the worm, 60 other gear means associated with the motor,

a worm engaging with the other gear means driven by the motor shaft and having the same gear ratio with the other gear means as the gear ratio of the worm with the first mentioned gear means, an electrical circuit 65 for controlling the motor, means responsive to a predetermined interval of time for completing the circuit, and means responsive to a predetermined arc of revolution of the last mentioned gear means for opening the 70 circuit.

6. The method of offsetting the effect of unequal cooling of the parts of a turbine rotor during intermittently idle periods comprising determining the rate of warping of 75 the rotor due to unequal cooling thereof when idle, and turning said rotor through 180 deg. before it has warped sufficiently to entail undesirable unbalance if started.

7. The method of offsetting the warping 80 of a turbine rotor due to an uneven distribution of heat throughout its mass when cooling during intermittently idle periods comprising, determining the period of time within which the maximum allowable warping 85 of the rotor occurs, and turning the rotor through 180 deg. within said period of time.

8. The method of offsetting the warping 90 of a turbine rotor due to an uneven distribution of heat throughout its mass when cooling during intermittently idle periods comprising, determining the period of time within which the maximum allowable warping 95 of the rotor occurs, and turning the rotor through 180 deg. at the termination of said period of time.

9. The method of maintaining a turbine rotor within safe limits of balance during intermittently idle periods where warping of the rotor occurs in an upward direction 100 due to unequal distribution of heat within its mass, comprising, determining the rate of warping of the rotor per unit of time, and turning said rotor sufficiently to place a different portion of its mass upward before it 105 warps beyond safe limits.

10. The method of maintaining a turbine rotor within safe limits of balance during intermittently idle periods where warping of the rotor occurs in an upward direction due 110 to unequal distribution of heat within its mass, comprising, determining the rate of warping of the rotor per unit of time, and turning said rotor to place a cooler portion of its mass upwards before it warps beyond 115 safe limits.

In testimony whereof, I have hereunto subscribed my name this 21st day of December, 1925.

ROBERT C. ALLEN.
